UNITED STATES PATENT OFFICE.

RICHARD ERNEST, OF NEW YORK, N. Y.

SHAMPOO-SHIELD.

No. 926,555.

Specification of Letters Patent.

Patented June 29, 1909.

Application filed March 2, 1908. Serial No. 418,730.

To all whom it may concern:

Be it known that I, RICHARD ERNEST, a citizen of the United States, residing at New York city, in the State of New York, have 5 invented certain new and useful Improvements in Shampoo-Shields, of which the following is a specification.

This invention relates to shampoo shields, and its object is, to provide an elastic shield 10 adapted to be fitted upon the head so that the front of the shield will rest upon the forehead below the hair, and the rear portion thereof will extend under the hair at the back of the neck to prevent the liquids employed 15 in shampooing, and the rinsing water from reaching the eyes, ears, or face, or the clothing of the user.

The invention comprises a shield of rubber or other elastic material formed with an 20 opening to adapt it to be fitted over the head and means for maintaining the shield in distended position.

The invention also consists of an elastic shield provided with a vizor or extension 25 over which the hair falls when the head is held over a bowl for the purpose of rinsing the hair.

The construction of the improvement will 30 be fully described hereinafter, in connection with the accompanying drawing which forms a part of this specification and its novel features will be set forth in the appended claims.

In the drawing:—Figure 1 is a view in perspective of a shampoo shield embodying the 35 invention. Fig. 2 is a similar view showing the shield in dotted lines and the head and hair in full lines, and Fig. 3 is a section on the line $x-x$ of Fig. 1 on an enlarged scale.

The shield 1 is of elliptical form and preferably made of thin rubber. It is formed with an opening 2 preferably of elliptical form to adapt the shield to fit the head of the user. The shield is provided at its front portion 40 with an extension 3 serving as a vizor. The outer edge of the shield is secured to a continuous resilient wire 4 by means of a facing 5 of rubber, said wire serving to give shape to the shield and reinforce its edges. A second 45 resilient wire 6 is secured to the shield adjacent to its inner edge by a facing 7 of rubber for the same purpose, and said inner edge is provided with a narrow hem 8. The portion 9 of the shield between the wire 6 50 and the hem 8 is thus left flexible to adapt it to closely grip around the head.

The improved shield is specially adapted for use in shampooing ladies' hair, and in the event that the person to be treated uses cosmetics or facial remedies of any character as 60 is not infrequently the case, it is highly important to effectually prevent water and other liquids from reaching the face. The manner of applying the shield to the head as 65 illustrated in the drawing accomplishes this end and the vizor 3 is an important feature of the device for this purpose, especially in the rinsing of the hair over a bowl.

The function of the vizor 3 is illustrated in Fig. 3, which shows the head in an inclined 70 position with the hair thrown forward over the vizor, the latter projecting the hair well away from the face, and preventing the dripping of liquid upon the face and neck 75 and the garments or clothing.

While the improved shield is primarily adapted for the shampooing of ladies' hair it is equally well adapted for men's use as will be apparent.

The vizor 3 is preferably formed integral 80 with the body portion of the shield as shown, but in this respect as in other minor details of construction the invention includes all such modifications and variations as may fall within the terms and scope of the claims. 85

Having thus described my invention what I desire to secure by Letters Patent and claim is:—

1. As an article of manufacture a substantially flat shampoo shield provided with an 90 opening, a reinforcement at the outer edge of the shield, and a reinforcement surrounding said opening.

2. As an article of manufacture a substantially flat shampoo shield of elastic material 95 provided with an opening adapted to conform with the shape of the head of the user, a reinforcement at the outer edge of the shield, and a reinforcement surrounding said opening. 100

3. As an article of manufacture a substantially flat shampoo shield of an elliptical contour, and formed with an elliptical opening, a reinforcement at the outer edge of the shield, and a reinforcement surrounding said elliptical opening. 105

RICHARD ERNEST.

In presence of—

HENRY A. MILLER,
GEORGE M. JUDD.
